UNITED STATES PATENT OFFICE.

ALPHONSO L. KOENIG, OF CHICAGO, ILLINOIS, ASSIGNOR TO THE KOENIG CARBONATORS, (INC.), A CORPORATION OF ILLINOIS.

CARBONATOR.

Application filed December 5, 1923. Serial No. 678,576.

My invention relates to apparatus for charging water or other liquid with a gas and dispensing the same, particularly that type of apparatus into which the water is delivered without requiring the use of a pump to raise the pressure of the incoming water above the normal working pressure of the gas in the carbonating chamber. In all apparatuses of this kind of which I am aware, it has been necessary to deliver the incoming water at considerable pressure, such pressure being applied to the operating of the control mechanism. Therefore, while apparatuses of this kind have been useful in places where water under pressure is available as, for example, in cities having a water works system, difficulty has often been experienced where it was necessary to draw the supply of water from a storage tank or other source which afforded only a low head or pressure on the water delivered therefrom.

The object of the present invention is to produce a simple and novel apparatus of the character described, which does not depend upon the pressure of the incoming water for its operation and will therefore work successfully and efficiently wherever there is a sufficient head of water to enable the water to flow by gravity to the apparatus.

The various features of novelty whereby my invention is characterized will hereinafter be pointed out with particularity in the claims; but for a full understanding of my invention and of its objects and advantages, reference may be had to the following detailed description taken in connection with the accompanying drawing, wherein:

Figure 1 is a view partly in side elevation and partly in vertical section through an apparatus arranged in accordance with the preferred form of my invention; Fig. 2 is a top plan view of the apparatus; Fig. 3 is a vertical section, on an enlarged scale, through the supporting means for the float and the elements directly actuated by the float; Fig. 4 is a detail on an enlarged scale showing a fragment of the controlling lever and trigger, and two of the four main valves, the latter being in section, in the same positions as in Fig. 1; Fig. 5 is a vertical section through the two valves that appear directly behind the valves in Fig. 4 and are controlled by the same lever that controls

the latter valves; Fig. 6 is a view similar to Fig. 4, showing the parts in the positions which they assume when the carbonating chamber is empty; Fig. 7 is a view similar to Fig. 5, showing the valves in the positions that correspond to the position shown in Fig. 6; Fig. 8 is a view similar to Figs. 4 and 6, showing the positions of the parts corresponding to a high liquid level in the carbonating chamber; Fig. 9 is a view similar to Figs. 5 and 7, the valves being in positions corresponding to the positions of the valves in Fig. 8; Fig. 10 is a view on an enlarged scale, looking at the right hand side of Fig. 1, only the trigger and its support being shown; and Fig. 11 is a section taken approximately on line 11-11 of Fig. 10 showing, in addition to what appears in Fig. 10 a fragment of the wall of the carbonating chamber, and a part of the float.

Referring to the drawings, 1 represents a sealed container of any usual or suitable size and shape, to which I shall refer as the carbonating chamber. Water or other liquid is delivered into this chamber through a pipe 2 extending downwardly through the top thereof, preferably at an angle to the vertical. The carbonating gas is delivered into the bottom of the chamber through a connection 3 between the bottom of the chamber and a pipe 4. The charged liquid is dispensed through a pipe 5 opening out of the chamber near the bottom thereof and leading to a suitable draught arm or other dispensing device, not shown. As the gas enters the bottom of the chamber it may be caused to carbonate the water in the chamber in a suitable way, the present invention having nothing to do with this detail. In the usual devices of this kind some of the gas passes up through the water and is collected in the top of the chamber, the pressure of this pocketed gas serving as means to force the liquid through the dispensing outlet when the latter is open.

In order that the apparatus may function efficiently in accordance with the purpose of this invention, it is necessary that whenever the chamber has been emptied of carbonated water, the pressure in the chamber be relieved and the water turned on so that it may flow by gravity into the chamber; it is also necessary that whenever the water in the chamber has risen to a predetermined level, the water inlet will be closed and the

pipe for delivering the carbonating gas be placed in open communication with the source of supply of gas. It is also desirable, in order to prevent waste of gas, that the supply of gas be shut off before the water has been completely emptied out of the chamber, because the pressure of the gas stored in the chamber will be sufficient for dispensing purposes even though no more gas be admitted into the chamber after the level of the water has dropped about two thirds of the distance from its highest point. All of the operations must be performed automatically and positively so as to insure against failure at any time.

All of the valve mechanism is controlled by a main controlling lever 6 arranged above the carbonating chamber and adapted to swing about a horizontal pivot 7. On one end of this lever is hung a heavy weight 8, while on the other end is hung what I shall term a bucket 9 closed both at the bottom and at the top, the relative masses of the empty bucket and the weight 8, and the relative proportions of the lever arms being such that the lever will be swung in the clockwise direction by the weight 8 when the bucket is empty and the lever is free to swing; while, when the bucket is full of water, the lever will be swung in the counter-clockwise direction by the bucket when the lever is not otherwise restrained. The bucket is adapted to be filled with water from the carbonating chamber, under certain conditions, through a flexible conduit 10 leading from the bottom of the bucket to and communicating with the interior of the carbonating chamber at a point 11 slightly below the lower end of the water pipe 2. There is a second flexible conduit 12 extending from the top of the bucket to the valve mechanism for the purpose, as will hereinafter be explained, of placing the top of the bucket and the top of the chamber in communication with each other.

The valve mechanism consists of four valves, shown in detail in Figs. 4 and 5 and also in Figs. 7 to 9. For the sake of simplicity I have shown the four valves as arranged in a single block or casing 14 resting on and fixed to the top of the carbonating chamber. In this block are four vertical valve chambers 15, 16, 17 and 18, two in front, viewing the apparatus as it appears in Fig. 1, and two directly behind those in front. Each valve chamber is divided into two compartments, a lower compartment and an upper compartment. Communication between the two compartments of each valve chamber is determined by four upwardly-seating valves 19, 20, 21 and 22. Beneath each valve is a spring 23 tending constantly to hold it against its seat. Each valve is provided with a stem 24 extending upwardly from the same through the top of

the valve casing. The valves may all be exactly alike and, for the sake of cheapness of manufacture and interchangeability in use, are preferably made so. The lever 6 is widened at the middle, as best shown in Fig. 2, so that portions thereof lie directly above all four of the valve stems. The pivotal axis of the lever lies midway between the two pairs of valve stems, that is, between the front and rear stems on one side and the front and rear stems on the other side. The parts are so proportioned that when the lever is horizontal it is out of engagement with all of the stems except that connected to valve 21, thus permitting all of the valves except the valve 21 to close; whereas, when the lever is swung in one direction it engages one pair of valve stems and forces the corresponding valves open and, when it is swung in the other direction, it engages the other pair of stems and forces the other two valves open.

The lower compartment of the valve chamber 15 communicates with a supply pipe 26 leading from a suitable source of compressed gas, not shown; whereas the upper compartment of this same valve chamber is connected with the upper end of the pipe 4. It will thus be seen that whenever the valve 19 is open, the bottom of the carbonating chamber is placed in direct communication with the supply of compressed gas, this communication being interrupted when the valve is closed. The other forward valve chamber 16 has its lower compartment in communication with the water pipe 2, while the upper compartment communicates with a water main 27. It will be seen that when the valve 20 is open, water may flow from the main 27 into the top of the carbonating chamber, the flow being stopped, however, when the valve is closed. The lower compartment of the valve chamber 17 which lies directly behind the chamber 15 communicates with the top of the carbonating chamber through a nipple 28. The upper compartment of this same valve chamber is in open communication with the flexible conduit 12 leading from the top of the bucket. Whenever the valve 21 is open, the top of the carbonating chamber is placed in direct communication with the top of the bucket, this communication being shut off when the valve 21 is closed. The fourth valve chamber 18, lying directly behind the chamber 16, has a vent 29 leading to atmosphere from the upper compartment therein. The lower compartment of this valve chamber is connected to the upper compartment of the chamber 17 by a conduit 30, best shown in Fig. 2 and in dotted lines in Figs. 5, 7 and 9. Whenever the valve 22 is open, the top of the bucket is vented to atmosphere through the conduit 12, the upper compartment of the valve chamber 17, the

- conduit 30, the valve chamber 18, and the vent 29. The top of the carbonating chamber can never be vented directly to atmosphere, because the valves 21 and 22 are never open at the same time, and therefore whenever the top of the carbonating chamber is in communication with the upper compartment of the valve chamber 17, by reason of the valve 21 being open and thus placing the interior of the carbonating chamber in communication with the lower compartment of the valve chamber 18, venting to atmosphere will be prevented because the valve 22 must at this time be closed.
- 15 The actuating lever for the valves is controlled by a trigger 31 which is in turn controlled by a float 321 arranged in the carbonating chamber. This trigger cooperates with several shoulders on the lever so as to serve to lock the lever in its various positions against the tendency of the weight or the bucket to move it, until the proper conditions have been brought about. In the arrangement shown, the actuating lever has 20 a depending arm 32 arranged at a short distance inward from the end on which the weight is hung. On the lower end of the arm is an upwardly-facing shoulder 33 lying outwardly of the arm. At some distance 25 above this shoulder is a downwardly facing shoulder 34. Still farther up is a second downwardly facing shoulder 35 lying outwardly of a vertical plane through the outermost point of the shoulder 34. At the 30 extreme upper end of the arm is an inwardly-directed notch 36 having a downwardly and outwardly sloping lower wall 37, at the extreme lower and outer end of which there may be placed a roller 37^a or 35 other anti-friction member; this notch extending inwardly at least as far and preferably farther than the vertical plane passing through the inner boundary of the downwardly facing shoulder 34. The trigger has 40 at its upper end an inwardly-directed finger 38, flat at the top. The lower edge of the finger is formed of a downwardly and outwardly inclined face 39 having approximately the same angle as the face 37 on the 45 lever, together with a short upwardly directed face 40 adjacent to the stem of the trigger; this latter face constituting a hook.
- The trigger is controlled primarily by the float. As best shown in Figs. 1, 3, 10 and 55 11, the float is fixed on one end of a rod or arm 41 that is pivotally supported, as indicated at 42, in a jaw 43 fixed to the wall of the carbonating chamber and lying in approximately the same vertical plane as the 60 main actuating lever. The jaw is carried on one end of a stem 44 passing through the wall of the carbonating chamber, the jaw forming what may be termed a head for the stem. The outer end of the stem is externally screw threaded and is provided with
- 5 a nut 45 that engages with a suitable cup-shaped washer 46, between which and the wall of the carbonating chamber lies a suitable packing material 47. A packing washer 48 may be placed between the head and the 10 inner face of the wall of the carbonator. Consequently, when the nut 45 is tightened, the support for the float will be rigidly connected through the wall of the carbonating chamber by an airtight and watertight joint. 15 That portion of the stem that lies within the thickness of the wall of the carbonator is preferably made square, as indicated at 491 in Fig. 1, and fits a square hole in said wall, to prevent the stem from turning. The 20 stem 44 is made tubular but has between the ends thereof a transverse partition 49. Within the chamber on the inner side of the partition is a sliding block 50 formed with an inwardly-directed jaw 51 containing an 25 anti-friction roller 52. The inner end of the float-supporting arm or rod is in the form of a comparatively thin vertical plate 53 entered into the jaw in the block 50 and having a cam edge 54 engaged with the roller 30 52. On the outer end of the stem 44 is screwed an elongated thimble 56 within which lies a piston-like follower 57. This follower lies at the inner end of the thimble, and between the same and the outer end of 35 the thimble is placed a strong spring 58 which tends constantly to force the follower inwardly. A small rod 59, arranged axially of the stem 44, passes through the partition 49 so as to engage at its inner end with the block 50 and at its outer end with the middle 40 of the follower 57. A plug 60 is screwed into the extreme outer end of the stem, and arranged between this plug and the transverse partition is a suitable packing 61 which will 45 prevent water or gas from escaping through the stem past the rod 59.
- The cam is so shaped that when the float is in its highest position, the block will be at the outer limit of its movement, the spring 58 being held under compression by the follower, whereas, when the float is in its lowermost position, the block will have been pushed inwardly by the action of the spring 58 which has expanded and forced the follower back against the rod 59.
- The follower 57 has attached to it a rod or shank 62 that extends axially of the thimble, in the outward direction, to the exterior of the thimble. The rod or shank 120 passes loosely through the middle point of a horizontal U-shaped yoke 63, the arms of which lie on opposite sides of the thimble and extend into proximity to the carbonating chamber where they are pivotally connected to the two arms 64 at the lower forked end of the trigger 31, the trigger being pivotally supported, as indicated at 65, on a lug 66 attached to or forming part of the wall of the carbonating chamber. The 125 130

parts are so proportioned that the trigger may swing about its pivot in the vertical plane containing the main actuating lever 6. Outward movements of the lower end of the trigger are limited by shoulders or nuts 67 on the rod or shank 62, while inward movements are permitted independently of this rod or shank against the resistance of a spring 68 surrounding the rod or shank 10 within the thimble, bearing at one end on the follower 57 and at the other end against a follower that bears against the inner face of the U-shaped yoke. This second follower may conveniently be in the form of two members 69 and 70 screw-threaded together so that the effective length of this follower may be varied, and slidable in the end wall of the thimble.

Operation.—In describing the operation 20 of my improved apparatus the cycle may be assumed to begin when the conditions are those illustrated in Fig. 1, namely, when the carbonating chamber remains about one third full of water during the process of 25 emptying it; the water being indicated at A. The actuating lever for the valves is now in its horizontal position, so that all of the valves except valve 21 are closed. The water which was contained in the bucket at one 30 time has been emptied into the carbonating chamber, so that the weight 8 tends to swing the lever in the clockwise direction, as viewed in Fig. 1.

No water or gas can enter, and therefore 35 the water that is drawn off and dispensed is forced out of the carbonating chamber by reason of the gas under pressure that is stored in the chamber above the charged water. As the water is dispensed, the liquid level in the carbonating chamber falls 40 and therefore the float also falls and permits the spring 58 gradually to force the follower 57 inwardly and thus draw inwardly the U-shaped yoke connected to the 45 lower end of the trigger. The trigger at this time is engaged with the shoulder 35 on the actuating lever but, as the yoke is gradually drawn in, the upper end of the trigger is gradually moved outward until it 50 clears the shoulder 35 and therefore removes the support for the actuating lever and permits the lever to drop quickly from the position indicated in Figs. 1 and 4 to that indicated in Fig. 6. As soon as the actuating lever reaches the position shown in 55 Fig. 6, the valves 20 and 22 are opened, while the valve 19 remains closed and valve 21 closes. The reason for leaving the valve 21 slightly open when the parts are in the 60 positions shown in Fig. 1, is to permit any small quantity of water that may have remained in the bucket to drain into the carbonating chamber through the flexible connection 10 while the bucket remains in the 65 position shown in Fig. 1. Consequently the

gas can flow freely from the carbonating chamber through the flexible conduit 10 and into and through the bucket as soon as the parts move into the positions shown in Fig. 6. Since the valve 22 is now open, the 70 bucket will be vented to atmosphere in the manner heretofore explained, through the upper flexible connection 12, the upper compartment of the valve chamber 17, the conduit 30, and through the valve chamber 18, 75 as can best be seen in Fig. 7. Consequently the pressure in the carbonating chamber will be released until the pressure drops to that of atmosphere. The water valve 20 is now open, as shown in Fig. 6 and, since the pressure in the carbonating chamber is only equal to atmosphere, water will flow by gravity into the carbonating chamber. As the water rises, the gas above the same will be forced out through the flexible connection 10 and the bucket to atmosphere, so that the incoming water meets with no resistance until it rises above the outlet end of the inclined water pipe 2. As soon as the water rises sufficiently high to cover the outlet end of the pipe 2, the gas remaining in the chamber above the water will be compressed to an extent depending upon the head of the incoming water. In order to insure that the water will flow successfully, there must be a slight head, even though it be due only to the employment of a storage tank lying a few feet above the carbonator. Consequently water will begin to flow through the flexible conduit 10 into the bucket 9 until the bucket is filled; the water tending to rise in the bucket to the same level as that of the source, and being permitted to rise in the bucket to a level sufficient to cause the bucket to overcome the counterweight 8 and the spring 68; because the top of the bucket is still venting to atmosphere, whereas the gas space in the top of the carbonating chamber is shut off from atmosphere and pressure is being built up therein.

During the time that the carbonating chamber is filling with water, the float is gradually rising, causing the trigger to be swung in the counter-clockwise direction, as viewed in Fig. 1 and Fig. 6, the actuating force being supplied from the follower 57 through the inner spring 68 and the secondary follower made up of the parts 69 and 70, so that the trigger will have been pressed laterally far enough to cause the finger to enter the notch 36. When the water reached such a level in the bucket 9 as to cause the bucket to begin to overbalance the weight 8, the lever began to swing in the counter-clockwise direction, but its movement was checked through the engagement of the inclined face 37 on the lever with the inclined face 39 on the trigger. The inclined faces of the lever and the trigger, respectively, are held together by the force of the spring 125 130

68 and, when the weight of the water in the bucket becomes sufficiently great, the resistance of the spring 68 will be overcome and the trigger end of the lever will rise, at the same time forcing the trigger out of the way by a wedging action. The resistance of the spring is slowly overcome but, when the inclined face 39 on the trigger comes in contact with the anti-friction roller 37^a, the resistance is quickly overcome and the trigger end of the lever rises with a snap action until its movement is arrested by the engagement of the shoulder 33 with the hook or downwardly-facing shoulder 40 on the trigger. During all this time the supply of gas has been shut off and the water valve has remained open. When the lever has completed its swinging movement in the direction under consideration, namely, slightly beyond the position shown in Fig. 8, the valves 20 and 22 are closed and the valves 19 and 21 are open, as shown in Figs. 8 and 9. Consequently, the supply of water is shut off and the vent to atmosphere is closed. At the same time, the gas valve 19, being opened, permits gas to flow into the bottom of the carbonator. Another result is that the valve 21 being opened, communication is established between the gas space in the top of the carbonating chamber and the top of the bucket, through the flexible conduit 12. The angular movements of the actuating lever are not very great and therefore, when the bucket, filled with water, is in its lowermost position, the level of the water therein is still above that in the carbonating chamber but, as soon as the top of the carbonating chamber is placed in open communication with the top of the bucket, water will flow from the bucket into the carbonating chamber until the level is the same in each. The partially emptied bucket therefore becomes too light to hold its end of the lever down and therefore the weight 8 swings the lever in the direction to raise the bucket. However, it is necessary that the gas valve remain open during the time that the greater part of the charged water is being dispensed, and therefore the lever must not be permitted to assume a horizontal position until it is time for the gas to be shut off. The trigger is still being pressed against the depending arm of the lever and therefore, as the trigger end of the lever starts to drop, the shoulder 34 will strike the upper end of the trigger, as shown in Fig. 8, thereby arresting further downward movement of the lever until the trigger has been released. The gas valve 19 and the valve for controlling communication between the tops of the carbonator chamber and the bucket, respectively, therefore remain open until the trigger is released to permit the lever to swing from its position shown in Fig. 8 to that shown in Fig. 4, whereupon the valve 19 closes while the other,

21, remains open. When the parts first are brought into the position shown in Fig. 8, the float is at the extreme upper limit of its movement and the two springs are compressed to the highest degree of compression 70 to which they are subjected during the operation of the apparatus. Consequently, as the float drops, due to the withdrawal of water for dispensing the same, the trigger will remain in engagement with the shoulder 75 34 until the cam associated with the float is moved to a position which permits the spring 58 to swing the trigger out of engagement with said shoulder. The cam is so proportioned that this occurs only when 80 the water in the carbonating chamber has fallen to such a level that it will be unnecessary to introduce more gas into the said chamber, namely, when the chamber has been emptied to about the point indicated in 85 Fig. 1. When this condition is reached, the end of the lever shown in Fig. 8 drops down but, because the shoulder 35 is arranged outwardly beyond the shoulder 34, the downward movement of the lever is arrested when 90 the shoulder 35 strikes the upper end of the trigger, as shown in Fig. 4; all of the valves except valve 21 being closed, and the water being thereafter dispensed under the pressure already in the carbonating chamber, as 95 heretofore explained.

The cycle of operations will be repeated automatically as liquid is drawn from the carbonating chamber, so that the latter will become automatically filled and the water 100 be automatically charged without undue waste of charging gas, and without regard to the pressure of the water at the source of supply, so long as the source is such as to afford a slight head which will cause the 105 water to flow freely when the water valve is opened.

If desired, the float-supporting arm 41 may have shoulders 70 formed in the vicinity of the supporting jaw 43, for engagement 110 with the jaw at the upper and lower limits of movement of the float.

It will thus be seen that I have produced a simple and novel liquid charging apparatus which will operate automatically, with 115 a minimum waste of charging gas, without the use of a motor and without requiring any greater pressure on the incoming water than is necessary to cause the water to flow freely by gravity into the charging apparatus.

While I have illustrated and described with particularity only a single preferred form of my invention, I do not desire to be limited to the exact structural details thus 125 illustrated and described; but intend to cover all forms and arrangements which come within the terms employed in the definitions of my invention constituting the appended claims.

I claim:

1. In combination, a carbonating chamber, a liquid-delivery pipe, a gas-delivery pipe, a float in said chamber, and means controlled jointly by said float and by the weight of a body of liquid that has been delivered to said chamber for opening and closing communication between said pipes and said chamber.
- 10 2. In combination, a carbonating chamber, a liquid-delivery pipe, a gas-delivery pipe, a float in said chamber, a vertically-movable bucket connected at the bottom to the chamber so as to receive liquid from the latter when the same rises above a predetermined level, and means controlled jointly by the bucket and the float for opening and closing communication between said pipes and said chamber.
- 15 3. In combination, a closed carbonating chamber, a liquid-delivery pipe, a gas-delivery pipe, a vent, a float in said chamber, a vertically-movable closed bucket connected at the bottom to the chamber to receive water therefrom when the liquid rises above a predetermined level; and means controlled jointly by said bucket and said float controlling communication between said pipes and said chamber, connecting and disconnecting the top of the bucket to said vent, and controlling connection between the top of the bucket and the top of said chamber.
- 25 4. In combination, a closed carbonating chamber, a liquid-delivery pipe, a gas-delivery pipe, a vent, a float in said chamber, a closed vertically-movable bucket, a flexible connection extending between the bottom of the bucket and the chamber at a point considerably below the top of the chamber, placing the chamber and the interior of the bucket in communication with each other; and means controlled jointly by said bucket and said float for controlling communication between said pipes and said chamber, connecting and disconnecting the top of the bucket to said vent, and controlling communication between the top of the bucket and the top of said chamber.
- 35 5. In combination, a closed carbonating chamber, a liquid-delivery pipe, a gas-delivery pipe, a float in said chamber, a closed vertically-movable bucket, a flexible connection extending between the bottom of the bucket and a point considerably below the top of the chamber placing the chamber and the interior of the bucket in communication with each other, the space in the chamber above the horizontal plane containing said point constituting a gas pocket; and means controlled jointly by said bucket and said float for controlling communication between said pipes and said chamber, controlling communication between the top of the bucket and said pocket, and at times venting said pocket and said bucket to atmosphere.
- 40 6. In combination, a carbonating chamber, a liquid-delivery pipe, a gas-delivery pipe, a float in said chamber, a vertically-movable bucket connected at the bottom to the chamber so as to receive liquid from the latter when the same rises above a predetermined level; valve mechanism for controlling communication between said pipes and said chamber and between the top of said bucket and said chamber, and between the top of the bucket and atmosphere; and means controlled jointly by said bucket and said float for causing said valve mechanism to operate to permit liquid to flow into the chamber when the liquid in the latter drops below a second predetermined level lower than the first-mentioned level and at the same time close communication between the top of the chamber and the top of the bucket and open communication between the top of the bucket and atmosphere.
- 45 7. In combination, a carbonating chamber, a liquid-delivery pipe, a gas-delivery pipe, a movable closed bucket, a flexible conduit connecting the bottom of the bucket with the said chamber at a point considerably below the top of the latter, a second flexible conduit connected to the top of the bucket, controlling valves for said pipes, valve mechanism for alternately connecting said second conduit to atmosphere and to the top of said chamber, a controller for said valves and said valve mechanism including a counterweighted lever supporting said bucket, a float in said chamber, and means controlled by the float to lock and release said lever.
- 50 8. In combination, a closed carbonating chamber, a liquid-delivery pipe, a gas-delivery pipe, a lever arranged adjacent to said chamber for swinging movements about a horizontal axis, a closed bucket carried by said lever and tending to swing it in one direction, a weight tending to swing the lever in the opposite direction, the weight being heavy enough to overcome the empty bucket, the bucket when filled being heavy enough to overcome the weight, a flexible connection between the bottom of the bucket and said chamber to permit liquid to enter the bucket from the chamber after it has risen to a predetermined level in the latter; valve mechanism actuated by said lever constructed and arranged to control communication between said pipes and said chamber, between the top of the bucket and the chamber, and between the top of the bucket and atmosphere; a trigger for locking the lever in various positions against any tendency it has to swing out of such positions; and a float in said chamber controlling said trigger.
- 55 9. In combination, a closed carbonating chamber, a liquid-delivery pipe, a gas-delivery pipe, a float in said chamber, a vertically-movable closed bucket, a flexible con-

nection between the bottom of the bucket and the chamber at a considerable distance below the top of the chamber, a valve for controlling communication between the liquid-delivery pipe and the chamber, a second valve for venting the top of the bucket to atmosphere, a third valve controlling communication between said gas-delivery pipe and said chamber, a fourth valve controlling communication between the top of the bucket and the top of said chamber, and means controlled jointly by said bucket and said float for actuating said valves.

10. In combination, a closed carbonating chamber, a liquid-delivery pipe, a gas-delivery pipe, a float in said chamber, a vertically-movable closed bucket, a flexible connection between the bottom of the bucket and the chamber at a considerable distance below the top of the chamber, a valve for controlling communication between the liquid-delivery pipe and the chamber, a second valve for venting the top of the bucket to atmosphere, a third valve controlling communication between said gas-delivery pipe and said chamber, a fourth valve controlling communication between the top of the bucket and the top of said chamber, and means controlled jointly by said bucket and said float for actuating first the first and the second valves and then the third and the fourth valves.

11. In combination, a closed carbonating chamber, a liquid-delivery pipe, a gas-delivery pipe, a float in said chamber, a vertically-movable closed bucket, a flexible con-

nection between the bottom of the bucket and the chamber at a considerable distance below the top of the chamber, a valve for controlling communication between the liquid-delivery pipe and the chamber, a second valve for venting the top of the bucket to atmosphere, a third valve controlling communication between said gas-delivery pipe and said chamber, a fourth valve controlling communication between the top of the bucket and the top of said chamber, a counterweighted lever supporting said bucket and cooperating with said valves to actuate the same, a trigger for holding the said lever in various positions, and means associated with said float for actuating the trigger.

12. In combination, a closed carbonating chamber, a liquid-delivery pipe, a gas-delivery pipe, a vent, a counter-weighted lever, a closed bucket carried by said lever, a connection between the lower end of said bucket and a point in the chamber located a considerable distance below the top of said chamber; valve mechanism controlling communication between said pipes and said chamber, between the top of the bucket and the top of the chamber, and between the bucket and atmosphere; said lever having a plurality of downwardly-facing shoulders and a plurality of upwardly-facing shoulders; a trigger cooperating with said shoulders on the lever; and a float in the chamber controlling said trigger.

In testimony whereof, I sign this specification.

ALPHONSO L. KOENIG.
